UNITED STATES PATENT OFFICE

JOSEPH F. KACENA, OF CHICAGO, ILLINOIS

WINDOW HOIST

Application filed May 23, 1928. Serial No. 279,925.

This invention relates to window hoists and the like. This hoist is particularly intended to be used for hoisting and dumping material into windows of buildings which are under construction.

An object of this invention is to provide a hoist which can be quickly and easily applied to an open window.

Another object is to provide means whereby the hoist is readily adjustable for windows of different widths and heights and one which at the same time is simple and efficient in its operation.

These and other objects, as will hereinafter appear, are accomplished by this invention which is fully described in the following specification and shown in the accompanying drawings in which—

Figure 1 is a vertical section through a window opening showing the hoist in side elevation;

Fig. 2 is a partial enlarged vertical section on the line 2 of Fig. 1;

Fig. 3 is a partial vertical section on the line 3 of Fig. 2;

Fig. 4 is a partial perspective view showing part of the main frame; and

Fig. 5 is a partial enlarged section on the line 5 of Fig. 1.

The embodiment illustrated comprises essentially two frames one of which lies within the window, while the other lies outside of the window. The inner frame consists of two vertical rods 10 one at each side of the window which are adapted to rest upon the floor 11 of a room, and these rods carry clips or the like 12 whereby a cross beam 13 consisting preferably of a pipe is located.

The outer frame previously referred to consists of two vertical members 14 which are also preferably pipes, and which are adapted to rest upon the outer portion of a window sill 15. The pipes 14 carry clips 16 which are secured thereto by U-bolts or the like 17, and these clips secure a horizontal pipe 18

to the vertical members 14. Eye-bolts 19 slidably engage the vertical members 10 and pass through openings in the lower part of the vertical members 14 and have wing-nuts 20 by which they may be tightened.

Eye-bolts 21 hook over the transverse rod 18 and are adapted to pass between cross braces 22 which, in turn, bear upon the vertical members 10. These eye-bolts are provided with wing-nuts 23 by which they may be tightened so as to clamp the inner and outer frames firmly upon the window opening. The transverse member 18 is provided with two spaced slings 24 which are firmly secured in place thereon together with lateral presses 25 by means of electrical welding or the like. These slings are made to extend some distance through the window opening and are provided on their lower edges with parallel inturned portions 24^a, the same being adapted to receive the lower portions of a boom 26 which in cross section is made in the form of an inverted U, as shown in Fig. 2.

T-bars 27 are secured to the lower inner edges of the boom 26 preferably formed from sheet steel, by riveting or welding. If desired, stiffening angles 28 may be similarly secured to the upper corners of the boom 26. The metal leg of the T-bars 27 serves as a bracket upon which is mounted a movable sheave frame 29 which carries a series of rollers 30 and which are adapted to roll upon the metal leg of the T-bars 27.

The frame 29 has depending portions 29^a through which passes a central pin 31 upon which is revolvably mounted a hoisting sheave 32. The boom 26, as a whole, is slideable back and forth through the slings 24, and this boom is first adjusted and then fixed in position by means of a chain 33 secured at one end to the boom and at the other to the cross brace 13 by means of a suitable hook 13^a thereon. The inner end of the boom 26 is then held down so as to tension the chain 33 by means of a chain 34 adjustably secured

90

to a hook 35 at the inner end of the boom, this chain being adapted to be secured through a turnbuckle 36 and a hook 37 to the floor joist 38.

5 A gravity-operated bucket 39 is provided with a bail 40 which is eccentrically mounted on the bucket by means of pivots 41 on two sides. These pivots, as shown in Fig. 1, are placed to the left of the center of the bucket, so that the weight of the bucket alone, or 10 of the bucket and contents, tends always to keep the bucket in the position shown in Fig. 1, in which the stop 42 is in contact with the bail 40. A handle 43 is provided for 15 ease in operating the bucket, as will herein-after be stated.

The bail 40 is secured to a suitable rope 44 which passes over the sheave 32 and down to a suitable hoisting drum (not shown).

20 The sheave frame 29 has an operating handle 45 pivotally secured thereto at 46. The outer end of this handle is bent down at 47 and overlies a bolt 48 which passes through lugs 24^a on the slings 24. This bolt is provided 25 with a wing-nut 49 by which the bolt may be tightened so as to firmly secure the slings 24 in adjusted position on the boom 26.

A bolt 48 striking the bent end 47 of the operating handle 45 serves as an outer stop 30 for the sheave frame 29. A clip 50 secured to the operating lever 45 provides a space into which the bolt 48 falls, as shown in Fig. 3.

35 The operation of this window hoist or derrick is as follows: The method of assembling the main frame in the window, as well as the method of adjusting the boom 26 in the sling 24 and then of anchoring this boom in place, will be readily understood from the foregoing description. Assuming that the parts 40 are in the position shown in Fig. 1, and that the bucket 39 which is filled with mortar or the like has been raised to the position shown in full lines, the operator grasps the extension 47 of the operating lever 45 and lifts the lever so that the clip 50 clears the bolt 48. He then draws in on the lever so as 45 to bring it to the position shown in dotted lines in Fig. 1, the sheave 32 then assuming 50 the dotted line position shown in this figure.

The operator then grasps the handle 43 on the bucket and tilts the bucket forward so that it dumps through the open window onto the floor 11. A suitable receptacle (not shown) is usually provided where mortar is thus dumped. The operator then rocks the bucket 39 back and its weight retains it in the normal position as shown in full lines. He then pushes the operating lever 45 back 55 to the position shown in Fig. 3, the clip 50 riding naturally over the pin 48 and dropping so as to lock the operating lever thereon.

60 It will be seen that I have provided a very simple and efficient form of window hoist which is readily adjusted to accommodate it-

self to windows of various size and height.

While I have shown and described but a single embodiment of my invention, it is to be understood that it is capable of many modifications. Changes, therefore, in the 70 construction and arrangement may be made which do not depart from the spirit and scope of the invention as covered by the appended claims.

I claim:

75 1. A window hoist comprising a frame adapted to be secured to a window opening, a boom of inverted U-shape cross section, a pair of sling members carried by said frame and adapted to lie one on each side of said boom and having inturned flanges adapted to engage and support the boom, and a sheave frame movable in said boom.

80 2. A window hoist comprising a frame adapted to be secured to a window opening, a boom of inverted U-shape cross section, means carried by said frame for supporting said boom intermediate the ends thereof, said boom being adjustable endwise in said holding means.

85 3. In a hoisting device, spaced frame members, means adjustably connecting said frame members to engage opposite side faces of a wall adjacent an opening, a sling pivotally carried by one of said frame members, a boom 90 slidably mounted in said sling to extend on opposite sides of said frame members, means adapted to secure said boom against sliding movement in said sling, means adjustably connecting one end of said boom to the other 95 frame member, a sheave block movable toward and from the other end of said boom, and means supported by the boom securing means for moving and securing said sheave block.

100 4. In a hoisting device, spaced frame members adapted to engage opposite side faces of a wall adjacent an opening, a sling pivotally carried by one of said frame members, a boom 105 slidably mounted in said sling, means adapted to secure said boom against sliding movement in said sling, and means adjustably connecting the boom to the other frame member.

110 5. In a hoisting device, spaced frame members adapted to engage opposite side faces of a wall adjacent an opening, a sling carried by one of said frame members, a boom 115 slidably carried by said sling, and means adjustably connecting the boom to the other frame member.

120 6. In a hoisting device, a supporting frame, a sling pivotally carried by said frame, a boom 125 slidably adjustable in said sling, and means adapted to secure said boom in angular adjustment about said sling pivot.

7. In a hoisting device, a supporting frame, a sling carried by said frame, a boom of inverted U-shaped cross section carried by said sling, tracks carried within said boom, a 130

sheave block movable on said tracks, and means movable through said boom and connected to said sheave block for advancing, retracting and securing said sheave block.

5 8. In a hoisting device, a frame, a boom of inverted U-shaped cross section carried by the frame, and a sheave supporting and operating device movable within the boom and having an operating handle depending from
10 said boom.

In testimony whereof, I have hereunto set my hand this 16th day of May, 1928.

JOSEPH F. KACENA.
